UNITED STATES PATENT OFFICE

2,660,410

HEAT EXCHANGER

Maurice H. Hofmeister, Evanston, Ill., assignor to
 Bell & Gossett Company, Morton Grove, Ill.,
 a corporation of Illinois

Application November 29, 1949, Serial No. 130,000

4 Claims. (Cl. 257—230)

1

My invention relates to heat exchangers and more particularly to an arrangement of this character including coils that are specially related for insertion through the wall of a steam or hot water boiler, or other kind of shell.

To provide a source of hot water, it is common practice to insert a heating coil through the wall of a boiler for exposure to hot water or steam as the case may be. For adequate heat transfer, it is necessary that a considerable length of tubing be employed to make the coil and, since flue passages within the boiler materially reduce the space available for installation and it is undesirable to make a single opening in the boiler wall to receive the coil because such an opening would so reduce the structural strength of the boiler that internal staying would be required, it is customary to form the coil in two or more, usually three, loops or banks which are inserted through a like number of spaced openings in the boiler wall. The openings are covered by a plate through which the inlet and outlet ends of the coil extend for connection to the system being serviced, but it is necessary to provide external, U-shaped pipe sections which are brazed to and provide connection between the adjacent ends of the loops which also project through the plate. This type of connection is unsightly, uneconomical to manufacture, and creates future points of leakage.

It is therefore one object of the invention to provide a heat exchanger of the general type indicated in which the only parts of the complete coil which extend through the cover plate are the inlet and outlet ends thereof.

A further object is to provide a heat exchanger including a coil having a plurality of loop components arranged for insertion through a like number of openings in a boiler wall, the adjacent ends of the components being connected by return bends which are disposed between the boiler wall and a plate covering the openings.

A further object is to devise a mounting for a heat exchanger coil composed of a plurality of loop components, the mounting consisting of a plate arranged to cover the openings through which the components extend into the associated shell and the plate including a pocket for receiving the return bends that connect the adjacent ends of the loop components.

These and further objects of the invention will be set forth in the following specification, reference being had to the accompanying drawing, and the novel means by which said objects are effectuated, will be definitely pointed out in the claims.

In the drawing:

2

Fig. 1 is a side elevation of a typical hot water boiler equipped with the heat exchanger.

Fig. 2 is a plan view of the boiler.

Fig. 3 is an enlarged section along the line 3—3 in Fig. 1.

By way of example, the invention will be described in connection with a hot water boiler, but it will be understood that the coil mounting is capable of use with any type of shell.

The numeral 10 designates a characteristic hot water boiler which may be connected to a heating system (not shown) by supply and return pipes 11 and 12, respectively, the boiler being cylindrical but may have other shapes. A plurality of vertically spaced openings 13, 14 and 15 are cut in the side wall of the boiler, with portions of the boiler wall designated by the numerals 16 and 17 intervening between the openings 13 and 14 and the openings 14 and 15, respectively. Preferably, the openings are elongated in shape with their major dimensions extending horizontally of the boiler, but the openings may have other shapes depending upon the marginal outline of the loop component which is inserted through the opening.

A plate 18 is attached to the boiler wall in enclosing relation to the openings 13, 14 and 15 and adjacent the bottom and top of the plate and forming a part thereof are hollow bosses 19 and 20 which register with the openings 13 and 15, all respectively. The plate is centrally offset outwardly from the boiler wall to provide a vertical pocket 21 which bridges across the opening 14, with the ends of the pocket communicating with the openings 13 and 15.

The exchanger coil 22 has its inlet and outlet ends projecting through the bosses 19 and 20, respectively, while that part of the coil which extends within the boiler is, in the present instance, arranged in a plurality of vertically spaced loops 23, 24 and 25 which are sized to be inserted through the openings 13, 14 and 15, respectively, parts of the coil indicated by the numerals 26 and 27 which connect the loops 23 and 24 and the loops 24 and 25 being located in the pocket 21 so that they extend around the wall portions 16 and 17, all respectively. In plan view, each loop may possess the flattened sinuous shape shown in Fig. 2, but the disclosure in this connection is intended to be largely diagrammatic since the loops may be arranged as desired so long as each may be inserted through its appropriate opening in the boiler wall. Further, the number of openings may be as low as two or any greater number depending upon operating requirements.

The coil and plate may be separately as-

3

sembled and installed as a unit in the boiler. Since only the inlet and outlet ends of the coil project through the plate, the number of openings therethrough, compared with present practice, is reduced. The parts of the tubing or pipe which connect the loops lie inwardly of the plate, thereby eliminating the present external loop construction with its possibilities for leakage.

I claim:

1. In a heat exchanger, the combination of a shell having a plurality of spaced openings in a wall thereof, a continuous pipe coil comprising a plurality of spaced loops each extending freely through an associated opening into the shell, and a plate secured to the wall in covering relation to the openings and offset to define with the included part of the wall a pocket communicating through the openings with the interior of the shell, the coil including pipe portions positioned in the pocket and serially flow connecting the loops and the inlet and outlet ends of the coil extending through selected openings, respectively, and tightly through the plate.

2. In a heat exchanger, the combination of a vertical shell having a plurality of vertically spaced openings in a side wall thereof, a continuous pipe coil comprising a plurality of generally horizontal loops spaced vertically to register with and extending freely through the openings, respectively, into the shell, and a plate secured to the wall in covering relation to the openings and offset along the vertical center line thereof to define with the included part of the wall a vertical elongated pocket communicating through the openings with the interior of the shell, the coil including vertically aligned, U-shaped, pipe portions positioned in the pocket and serially flow connecting the loops and the inlet and outlet ends of the coil extending through selected wall openings, respectively, and tightly through the plate.

3. In a heat exchanger, the combination of a shell having a plurality of spaced openings in a wall thereof, and an assembly mounted as a unit on the shell comprising a continuous pipe coil including a plurality of spaced loops each extend-

5

ing freely through an associated opening into the shell, and a plate secured to the wall in covering relation to the openings and offset to define with the included part of the wall a pocket communicating through the openings with the interior of the shell, the coil including pipe portions positioned in the pocket and serially flow connecting the loops and the inlet and outlet ends of the coil extending through selected wall openings, respectively, and tightly through the plate in supported relation thereto.

4. In a heat exchanger having a shell provided with a plurality of spaced openings in a side wall thereof, the combination of a continuous pipe coil comprising a plurality of spaced, parallel loops adapted to extend freely through the openings, respectively, into the shell, and a plate adapted for securement to the wall in covering relation to the openings and offset to provide an elongated pocket normal to the loops and arranged to communicate through the openings with the interior of the shell, the coil including aligned U-bends positioned in the pocket for serially flow connecting the loops and the inlet and outlet ends of the coil extending tightly through and being carried by the plate.

MAURICE H. HOFMEISTER.
